DRY DOCK PONTOON CONSTRUCTION

Frederic R. Harris, New York, N. Y.

Application August 7, 1943, Serial No. 497,784

11 Claims. (Cl. 114—83)

1

This invention relates to the construction of hulls and especially pontoon hulls for floating dry docks.

An important object of the invention is to provide an improved internal framework for a dry dock pontoon, comprising a novel and advantageous arrangement of bulkheads and cooperating trusses.

The floating dry dock, adapted to lift a ship out of water and properly support it for repairs, has undergone much recent development in keeping with modern progress in the design of ships. At first a marine vessel comprised a shell internally braced by transverse frames, rigidly connected to a central keel, which extended over the vessel's entire length. Therefore, in a dock, the whole ship load could be supported on blocks directly under the keel, which was the strongest part of the ship. Bilge blocks were added at the sides merely to balance the vessel on the keel blocks.

The keel was afterwards replaced by a shallow double bottom which, however, did not in any substantial manner change the docking conditions; and floating dry docks were designed as before to take the entire load on a central row or track of blocks, which were still of timber and bore the full weight of the vessel without crushing.

But at the present day there are both commercial and naval vessels of such great size and weight that, even should a continuous keel track be provided the whole length of the dock, this track would have to be so broad that a substantial portion of the ship's bottom would be covered thereby and made inaccessible to workmen. The remedy for this is a plurality of tracks or rows of blocks, side by side on the floor of the dock; and a structural design for the dock that is economical in the amount of material used, and yet firm enough to withstand all working stresses due to the vessel's weight, and other forces.

In floating dry docks of prior construction a rugged, central longitudinal bulkhead is usually included; with a considerable number of transverse bulkheads. My invention contemplates several bulkheads for carrying and sharing the weight of the ship; and both the ship load and the buoyancy load are transmitted to said bulkheads by a system of frame-trusses; and thence to additional bulkheads which intersect the first, and complete the framework of the hull of the dock. The result is great strength and a large saving in structural material.

The invention will be described in connection

2

with a pontoon of a multiple-unit dry dock; that is, a dry dock that is made up of a number of similar pontoons connected together side by side to form a long dock for supporting a ship; as set forth in my application for patent on a Multiple-unit floating dry dock, Serial No. 482,376, filed April 9, 1943, now Patent No. 2,379,904, dated July 10, 1945. But the invention is not limited to pontoons of multiple-unit docks, and some features of the invention relate to hull construction generally.

My invention provides bulkheads arranged so as to extend crosswise of a ship in the entire dock, and placed some distance apart, and a series of trusses containing K frames on both sides of each of said bulkheads. Horizontal beam members to resist compression extend from side to side of the hull of the pontoon and unite the centers of the K frames in the different trusses; and the frames at each side are further braced by beams connecting their centers. Thus the trusses are stiffened in their various positions and, with their increased rigidity, are able to support high compression loads. The span of the uprights in the trusses becomes half of that in a prior floating dry dock. The horizontal beam members in their turn, being joined rigidly together, will resist effectively the outside water pressures on the sides and ends of the pontoon.

Also my invention renders it feasible to rely upon relatively few bulkheads to transmit inherent pontoon truss-bending stresses. The K frame trusses which, at their ends are secured to some of the bulkheads, will, together with the additional bulkheads and their plating between the trusses, render the whole interior framework so strong and rigid that all liability of warping and similar strains in the bulkheads is eliminated. Also the trusses render the deck and bottom so rigid that the entire deck and bottom plating will act as flanges for girders, the webs of which are formed by the additional bulkheads; and buckling and other distortion of deck and bottom plates becomes impossible.

In addition, my invention contemplates sufficient additional reinforcement in the central part of the pontoon hull to cooperate with the bulkheads and trusses in realizing the full aim of the invention.

Another feature of the invention relates to a combination of bulkheads and trusses within the pontoon by which loads are transmitted to some bulkheads and through them to additional bulkheads. In the embodiment of the invention illustrated, the trusses and the various bulkheads

are all connected together to form a unitary structure inside the hull.

A more specific object of the invention is to transmit deck load and buoyancy loads through parallel K frame trusses to bulkheads at the opposite ends of the trusses, and from these bulkheads to additional bulkheads within the pontoon connected to and intersecting the first bulkheads.

A further feature of the construction is that the bulkheads are of a composite structure that is thicker at the places where each bulkhead meets another bulkhead extending in a transverse direction. This construction may comprise solid columns located where the planes of the bulkheads intersect, the respective bulkheads being made up of sections connected with the solid columns in such a way that the column is structurally a part of the composite bulkheads.

Dry dock pontoons made in accordance with this invention have a number of bulkheads with parallel trusses between and on each side of the latter, bulkheads at the opposite ends of the trusses and under the wing wall sections on the pontoon, and other trusses beyond the last named bulkheads and less closely spaced. In this way the greatest strength is concentrated under the portion of the pontoon deck that supports the ship, and less strength is needed adjacent the ends of the pontoon where smaller stresses are encountered.

Some features of the invention relate also to the connection of structural members and to special joints that are particularly suitable for welded connections in ship construction and other objects, features and advantages of the invention will appear or be pointed out as the description proceeds.

In the drawings, forming a part hereof, and in which like reference characters designate corresponding parts in all the views,

Figure 13 is an enlarged sectional view taken on the line 13—13 of Figure 12; and

Figure 14 is an enlarged perspective view taken on the section line 14—14 of Figure 12.

A pontoon hull 20 (Figure 2) has bulkheads 21

to 24 running from side to side, fore and aft of the middle of the pontoon; and bulkheads 25 and 26 extending from end to end. All bulkheads are rigidly united at the intersections. There is a buoyancy chamber in the pontoon between the bulkheads 22 and 23, but all of the other compartments formed within the hull by the bulkheads are preferably flooding compartments for sinking the dry dock. The location of the starboard wing wall section carried by the pontoon is indicated at 28, and of the port wing wall section by the broken lines 29. Framing trusses 30 extend parallel to the bulkheads 25 and 26 on both sides of each, with extensions at intervals beyond the bulkheads 21 and 24 running out to the ends of the pontoon as seen in Figures 1 and 8. These trusses occupy most of the interior of hull, but are supplemented by a pair of trusses 30a and extensions 31a (Figures 1 and 2) one at each of the longer sides of the pontoon.

The trusses 30 rigidly connect the transverse bulkheads 21 and 22 in the port half of the pontoon and the bulkheads 23 and 24 in the starboard half of the pontoon. Beyond the bulkheads 21 and 24 the extensions are indicated at 31; these are not so close together as the trusses 30. In the illustrated embodiment, every other one of the trusses 30, with reference to either of the bulkheads 25 and 26, has an extension 31. Each of these trusses and extensions, and each side truss 30a and its extension 31a form a single continuous reinforcing truss member. The trusses 30 may be continued across the buoyancy chamber at a suitable number of points, if desired; see the broken lines between the bulkheads 22 and 23 in Figure 2.

The bulkheads 25 and 26 are continuous and traverse the width of the buoyancy chamber between the bulkheads 22 and 23. Between the latter bulkheads the hull is further reinforced and braced as set forth below to give it the strength required. When the pontoon is assembled side by side with other pontoons to make a dock, as set forth in my above-mentioned application, with the bulkheads 21, 22, 23 and 24 and the wing wall sections on each of the pontoons all in alignment with these bulkheads and wall sections of the other pontoons; and a ship is moved in for repairs; the weight of the ship is borne upon keel blocks, indicated at K, Figure 2 on the floor or deck of the dock, in the middle; and bilge blocks, indicated at B set up near the lines of the bulkheads 21 and 24. Each row of blocks bears about one-third of the total weight of the vessel.

I shall first describe the outer trusses 30a and the extensions 31a within the pontoon at each long side of the hull, parallel to the bulkheads 25 and 26, as shown in Figure 1. This sectional view illustrates deck plating 32 and a top beam 33, also parallel to the bulkheads 25 and 26; and reinforcing elements 34 arranged crosswise thereof. The pontoon has bottom plating 36 with similar elements 37 and bottom chords or beams 38, extending in the same direction as beams 33. The beams 33 and 38 and the members 34 and 37 lie between the bulkheads 21 and 22, 23 and 24. Between the extremities of the pontoon and the bulkheads 21 and 24 these beams are extended in somewhat modified cross-sectional form as shown at 33' and 38' (Figure 1) and the connecting reinforcing elements 34' and 37' are in the same part of the pontoon. At the very ends, fore and aft, each of the beams 33' widens

out into a broad web and runs up to the deck, as shown in Figure 1 at 38a.

Along these sides, further, between bulkheads 21 and 22, 23 and 24, and beyond the bulkheads 21 and 24, uprights 39 unite the upper beams 33 and their extensions 33'; at their junctions with the upper members 34 and 34'; to the lower beams 33 and 33' at their points of intersection with the lower members 37 and 37'. Alternate uprights 39, which are I-shaped in cross-section, of trusses 30a and all uprights in extensions 31a are connected with the top beam 33 and 33' and lower beams 33 and 33' by diagonal braces 40. These braces 40 are made fast to the uprights 39, at points midway between the upper and lower ends thereof, by gusset plates 41, to form frames that are K-shaped. All of the uprights 39 are connected at the same points with horizontal braces or channel beams 42, which join the K-frames of each truss at their centers. Beams 42 are also affixed to the bulkhead at the buoyancy chamber and to a plate 38b at the edge of the web 38a.

There are horizontal stiffening members or ribs 44 secured to the bulkheads 21, 22, 23 and 24. A rectangular coaming 46 is secured on the deck of the pontoon at each end and serves as the support for the section of the wing wall which is there mounted on the pontoon. Each coaming extends across the pontoon's full width and its two long sides lie in approximately the plane of the outermost uprights 39, and the plane of the nearest bulkhead 21 or 24.

On one face of each of the bulkheads 22 and 23 at each side of the middle of the pontoon are vertical stiffening ribs 23a, T-shaped in cross-section, presented to the bulkheads 21 and 24 and anchoring the adjacent ends of the channel beams 42. These ribs are welded to the deck and bottom beams 33 and 38. At their junction with the latter are gussets 48a to which the lower ends of the adjacent diagonal braces 40 are welded. Between each of the bulkheads 22 and 23 and the outer ones 21 and 24, the uprights 39 and braces 40 are illustrated as providing four K-frames, starting at the former and ending at the latter; and two more such frames beyond bulkheads 21 and 24. All diagonal braces 40 are welded to the faces of the plates 41 which are in turn welded along one edge to the edges of the flanges of uprights 39; and the outer faces of the bulkheads 21 and 24 are also reinforced in the planes of the trusses 31a by vertical ribs 39' comprising angle beams welded along their outer edges, as shown in Figure 1.

Figure 4 shows the connection between the diagonal braces 40 and the beams 33 and 38 and their extensions. Each diagonal brace 40 is an angle member and attached to the top of the beam shown for example at 38, with one of its flanges vertical and in the vertical plane of the web of the beam. The brace is bevelled off even with the top of the beam, and the other or side flange of the brace rests on the top of the beam. An extension 47 is welded to the web and the flange of the beam and to the end of the side flange of the brace in such a position that it forms, in effect, a continuation of the other or side flange of the diagonal brace 40.

A splice plate 48 has its upper portion welded edgewise to the outside or back of the vertical flange of each diagonal brace 40, and its lower portion welded to the remaining face of the vertical web of the beam 38. The cut-out or recessed portions 49 (Figure 3) of the parts 47 and 48 are for fitting the edges of the flange 75 of the pontoon to the channel beam 42 on the other and

of the beam 38. The top braces are similarly secured at their upper ends.

Between each of the outer bulkheads 24 and 21, and the ends of the pontoon, the two additional K-frames along the sides have their centers in similar uprights; and are attached to the beams 33' and 38' in the same way; except that the diagonal braces of the first are made fast at their ends near the deck and bottom beam extensions to the upright reinforcements 39' upon said bulkheads. The channel beams 42 extend from said bulkheads through these two K-frames also and are joined, as already stated, to the widened portions 38a of the beams at the ends of the pontoon. These beams are pieced at the bulkheads 21 and 24, and securely welded thereto.

Thus a complete truss or girder made up of K-frames extends from each bulkhead 22 and 23 out past the bulkheads 21 or 24 to the two ends of the pontoon along either side.

Figure 5 shows the design and arrangement of these trusses 31a along the sides, beyond the longitudinal bulkhead 24; the plan beyond the bulkhead 21 being the same. This view also depicts the longer bulkheads 25 and 26 and with stiffening ribs 44 extending horizontally along same and the intersecting bulkheads. Manholes such as appear at 51 are provided near the lower end of the bulkheads 21 and 24 for access from one compartment to another. When the dry dock pontoon is in use, each manhole 51 is preferably closed by a plate, and each of the compartments is provided with its own piping for flooding or pumping water from the compartment. Similar manholes are provided in the other bulkheads wherever needed.

The construction of the trusses 30 and the extensions 31 is best illustrated in Figures 5, 6 and 8. The trusses 30 include horizontal upper chord members made of beams 52 and lower chord members embracing beams 53, connected together by upright beams or columns 54 and diagonal braces 56. Each deck chord consists of two parallel beams 52, each bottom chord of similar beams 53, extending from the bulkheads 22 and 23 out to the bulkheads 21 and 24. They lie between and outside of the bulkheads 25 and 26. The diagonal braces 56 comprise opposed angle bars connected together by batten plates 57. The trusses all have uprights 54 that are I-shaped in cross section. A section through the trusses 30 is shown in Figure 6 to indicate how the uprights 54 are inserted at their ends between the beams 52 and 53 and united thereto; the braces 56 having their ends attached to these chords in the same manner.

The braces 56 are omitted from Figure 6 for the sake of clearness. But Figure 7 illustrates the manner in which the diagonal braces 56 of the trusses 30 are connected with the uprights 54 at approximately the mid-points of the latter, by means of gusset plates 59 welded to the flanges of the braces and uprights. The trusses 30 are cross-connected with one another by channel beams 43, welded to the outside surfaces of the flanges of the uprights 54, with reinforcing plates 58 welded to the inside faces of the flanges and to the webs of the uprights 54 in such a position as to form, in effect, a continuation of the sides of the channel beams 43. This construction gives the cross beams 43 the same strength as if they were continuous, and at the same time does not weaken the uprights 54 by cutting through their flanges. The beams 43 join the centers of the K-frames from the channel beam 42 on one side

are rigid with the bulkheads 25 and 26 where they connect with same. These beams reduce the free, effective span of all the uprights in the trusses by half, and reduces the amount of material otherwise needed. The construction of the truss extensions 31 is similar to that of the trusses 30.

Figures 1 and 6 show the K-trusses 30 arranged relatively close together between bulkheads 21 and 22, 23 and 24; and Figure 5 shows how the truss extensions 31 are farther apart in the spaces between the bulkheads 21 and 24 and the ends of the pontoon. On either side of each of the bulkheads 25 and 26, the extensions 31 coincide with and are continuations of every second truss 30. In Figure 5 the positions of the trusses 30 not extended are indicated by the plates 59.

Figure 9 shows the bottom chord or beam structure of truss 30, between the bulkheads 21 and 22, 23 and 24. Parallel structural members, preferably T-sections 61, with the bottom plates 36 of the pontoon welded to them, have the webs extending upward, and angle bars 62 are welded to the upper edges of the webs of the T-sections 61, the remaining flanges of the angle bars extending outward. The angle bars 62 are connected by batten plates 63 at spaced points along their length to give a chord that is compound in structure. There are limber holes 64 along the lengths of the T-sections 61 for the passage of water. The top chord with beams 52 is similar. The deck and bottom beams 52 and 53 are cross-braced at the requisite number of points by ribs 34 and 37 respectively, rigidly attached to said beams.

Figure 10 shows the union of the bulkheads and the pontoon deck and bottom plating. The bottom edge, for example, of the plating of the bulkhead 25 is shown welded to the upstanding web of a T-beam 66. The bottom plating is welded to the flange of this beam. All the bulkheads may similarly be connected with the top and bottom plating of the pontoon hull.

Figure 11 shows the construction of the bottom chord of each truss extension 31 near the ends of the hull, at the places where it is intersected by bottom stiffening ribs 31a. These ribs are preferably constructed with recesses along their lower edges, to which are welded the bottom plates 36. The recessed or serrated edges also allow passage of water. The bottom chord construction of Figure 11 involving the parallel beams 53' differs from Figure 9 in that flat bars 61' take the place of the T-sections 61, for in the truss extensions 31 less strength is required. The beams 53' of these extensions are thus cross-braced by ribs 37a fastened thereto at various points.

Each upper chord of the truss extensions 31 comprises similar parallel beams 52' between the bulkheads 21 and 24 and the ends of the pontoon of slightly less height than the beams 52. These beams 52' are also cross-connected along their edges, and cross ribs 34' of any suitable size and shape are attached between these beams.

In the trusses 30, the bottom ends of the lower braces 56 are anchored further between gusset plates 56a and 56b adjacent the lower beams 53, and welded to these plates. Reinforcing ribs 23' on the faces of the bulkhead 23 (and 22) connect the deck beams 52 to the bottom beams 53, and the plates 56a unite these ribs to the beams 53. The plates 56b are attached to the beams 53 and lower ends of uprights 54, and the lower ends of adjacent braces 56 and uprights 54 are between them and beams 53 and attached to same. The braces 56' of the extensions 31 (ex-

cept adjacent the bulkheads 21 and 24) are also reinforced by similar plates 56b at their junctions with upper and lower beams 52' and 53'. The braces 56' of the extensions 31 nearest to the bulkheads named are secured above and below with their ends partly between the beams 52' and 53', and reinforcing ribs 54a, attached to the adjacent faces of these bulkheads and uniting the deck beams 52' and bottom beams 53'. The uprights 54 and braces 56 as stated above, are enveloped at their ends by the beams 52 and 53 and welded to the inner face of the bars 61 and 62. The uprights 54' of the trusses 31 are welded at their ends to the beams 52' and 53' at the flanges thereof; and the angle-bar braces 56' are welded to the inside faces of these beams, the same as the braces 56.

The terminal K frames of trusses 31 at bow and stern, comprising diagonal braces 56' joined at deck and bottom to beams 52' and 53' are secured at their adjacent ends to gussets 58' on partitions or auxiliary bulkheads 59 extending across the extremities of the pontoon. The beams 52' and 53' terminate at these partitions and the remaining space is braced and divided as may be necessary.

Figure 13 illustrates the manner in which the six bulkheads are connected with one another. Each of the bulkheads 25 (and 26) is of composite construction and comprises plates or webs 68 between bulkheads 21 and 22, 23 and 24, connected at one end with a solid column 69.

Each of the bulkheads 25 and 26 also includes plates 68' beyond bulkheads 21 and 24, connected to the other sides of the solid columns 69. Such a column 69 is located at each junction of the bulkheads 25 and 26 with the bulkheads 21 and 24. The bulkheads 21 and 24 are made up of plates or webs welded to opposite sides of the column 69.

Each column 69 is considerably thicker than the plates 68 but is preferably provided with vertical stiffening ribs 70 comprising T-sections welded to one side. The portions of the bulkheads 25 and 26 that extend through the buoyancy chamber are made of plates 71 much thicker than the plates 68 in order to provide greater strength between the bulkheads 22 and 23, which are subject to considerable pressure when the pontoon is flooded. For clearness the parts 69 and 70 are omitted in Figure 8.

Figure 14 shows the construction by which the bulkheads 25 and 26 are reinforced. In addition to the horizontal ribs 44 with serrated edges welded to the face of the bulkheads, there are upright flat bars or plates 73 welded to the bulkheads and the outer edge of each bar or plate 73 is stiffened by a T-bar 74 welded to the edge of plate 73. The stiffening ribs 44 extend through openings in the plates 73. For the sake of clearness, these ribs 44 have not been shown in Figure 8.

The horizontal channel beams 43 uniting the K-frames of trusses 30 and 39a and extensions 31 and 31a are also attached to the bulkheads 25 and 26 in sections; one length having its end welded to the flange of the T-bar 74 and another length being connected with the other side of the bulkhead 25 by a gusset plate 76. There are plates or bars 77 between the flanges of the T-bars and bulkheads that form in effect continuation of the channel beams 43.

The construction at the sides of the pontoon between the outermost trusses 30a and 31a is indicated in Figures 5 and 6 but need not be

detailed herein. These parts are reinforced and divided between the sides and the uprights 39; so as to support the outside plating and close the pontoon, but the load stresses fall upon the trusses only.

All of the connections described herein are welded, but the invention is not limited to welded joints and seams and some members can be used with rivets or other fastenings. Various changes and modifications can be made and some of the features of the invention can be used without others.

In the trusses 30a and 31a the uprights 39 all have the same dimensions; and so do the upper braces 40. The lower braces 40 are a bit lighter except the one nearest the end, which is of the same size as the top braces. The lower braces are stressed more evenly by the buoyancy load; but at the outer end of the extension 31a the upward bending moment is greatest. Hence the lower brace 40 at this point should be somewhat stronger.

As for the trusses 30 and 31 the uprights 54 and 54' are all a bit lighter than the uprights 39, but those of the extensions 31 are heavier and stronger than in the trusses 30. The K-frames of these trusses 30 and the extensions 31 are also lighter than in the trusses 30a and 31a but are so designed that the braces 56' at the ends of the pontoon can well resist the upward bending moment due to buoyancy; and the braces in the extensions 31a at the bulkheads 21 and 24 are suited to the weight loads of ship and wing wall section above and buoyancy below. The upper braces in the trusses 30 between the bulkheads 21 and 22, 23 and 24 are lighter than in the trusses 30a; and the remaining braces, upper and lower, in both trusses 30 and extensions 31, especially the upper and lower braces in the three remaining K-frames of the latter between the K-frames at the ends thereof and bulkheads 21 and 24 are lighter still than in extensions 31a because the stresses are less and those due to the buoyancy loads are evenly distributed.

The central buoyancy chamber between the bulkheads 22 and 23, has a relatively light central bulkhead 18 and is traversed by the two long bulkheads 25 and 26. This chamber also contains room for machinery, crew's quarters, storage and fuel space, etc. Between the bulkheads 22 and 23 are reinforcing members 52A which are in line with the chords containing the members 52 and 52'; thus forming composite beams that are continuous from end to end of the hull. The waist of the hull containing this chamber is further reinforced by flooring and other members as required.

The unit stresses due to buoyancy load are reduced because the pontoon is lengthened beyond the wing wall locations. At the same time a more efficient beam effect is produced by the tapering ends of the hull.

It will be noted that the trusses 30-30a are all relatively close together. Hence only two bulkheads 25 and 26 running from end to end are needed; and in a pontoon 250 feet long by 80 feet beam, for example, these bulkheads will be over 30 feet apart. The trusses stiffen the other bulkheads and enable them to withstand the weight of ship and wing wall sections. Both 70 weight loads and buoyancy loads are transmitted by the trusses to the bulkheads 21, 22, 23 and 24; and through these to the bulkheads 25 and 26. In the usual design of dry dock pontoon, with a single central bulkhead parallel to the side walls,

transverse bulkheads running in the same direction as bulkheads 25 and 26 are added in such number that in a structure of the dimensions specified above, they will be only 8 feet apart.

5 The replacement of most of these by K-trusses affords a great saving in steel, without loss of strength. The trusses make the bulkheads 21 to 24 rigid; these in turn, especially in combination with the cross beams 43 uniting the K-frames of the different trusses, stiffen the bulkheads 25 and 26 so as to obviate all risk of buckling, warping or other distortion. These cross beams also brace the side plating to the extent demanded against the outside pressure of the water; the bulkheads 25 and 26 and channel beams 42, and trusses 31 and 31a also having the like result with respect to the outer plating at the ends. The general effect is to make the bulkhead, framework and deck and bottom plating so rigid that the bulkheads virtually become girders; with the deck and bottom plating serving as the flanges, and the bulkheads themselves as the webs; and the cross-beams 43 have the additional utility of so bracing the K-frames at the centers that the spans of the uprights 39, 54 and 54' is only half their length. This too, increases the strength and contributes to the general saving in materials of construction.

As indicated in Figures 8 and 12, only the extension 31 in the very middle of the pontoon will have five K-frames. Those at each side will have fewer because the hull is ship-shaped, as set forth in my co-pending application for patent above mentioned. The transverse end bulkheads 59 are of less height at the ends where they are attached to the bulkheads 25 and 26 (Figure 12). The lower edges of these bulkheads curve upward near the extremities as Figures 8 and 12 illustrate. But the four cross-beams 43 of the extensions 31 extend all the way across the ends from one side to the other.

The deck and bottom plating reinforcing ribs, beams, uprights, braces, bulkheads and all other members, are securely welded in their various parts and in their respective positions to make the pontoon as strong as possible at all points. The construction described is well adapted to attain all the objects of the invention.

Having described my invention, what I believe to be new and desire to secure and protect by Letters Patent of the United States is:

1. In a hull for a dry dock the combination of trusses, each of which has a deck beam, a bottom beam, uprights connecting said beams, braces uniting said beams to points between the ends of the uprights, and beams uniting said trusses to one another at said points.

2. A hull for a dry dock pontoon containing trusses, each of which includes a deck beam, a bottom beam, uprights between the beams, diagonal braces connecting the uprights at points intermediate their upper and lower ends to said beams, a beam uniting said uprights of each truss at said points, and cross-beams connecting the trusses together at said points.

3. A hull for a dry dock pontoon containing longitudinal bulkheads, transverse bulkheads intersecting said longitudinal bulkheads adjacent the ends of said pontoon, vertical columns at the intersections, said columns being of greater thickness than the bulkheads and said bulkheads being made up of sections that have their ends permanently connected with said columns throughout the length of the latter, and a transverse bulkhead at each side of the middle of the

11

pontoon intersecting the longitudinal bulkheads, the latter being of greater thickness between the last-named transverse bulkheads.

4. A hull for a dry dock pontoon having intersecting, rigidly connected bulkheads and trusses comprising K-frames crossing some of said bulkheads and fixed thereto, said trusses being substantially parallel to the remaining bulkheads, and connected transversely to one another adjacent the midpoints of said frames.

5. A hull for a dry dock pontoon, comprising a pair of bulkheads between each end and the middle of the hull, additional bulkheads extending from end to end intersecting and united with the aforesaid bulkheads, and trusses parallel with said additional bulkheads, said trusses uniting the members of each pair of the aforesaid bulkheads, and some of said trusses being extended beyond them towards each adjacent end of the hull.

6. The hull according to claim 5, having cross beams at predetermined points connecting said trusses and said additional bulkheads.

7. A hull for a dry dock pontoon having a pair of bulkheads between the middle and each end, additional bulkheads extending from end to end and intersecting and united with both pairs of bulkheads, trusses comprising K-frames between and along the outer sides of the additional bulkheads, said trusses connecting the aforesaid bulkheads of each pair together, some of said trusses extending out to the adjacent ends, and a beam connecting the K-frames of some of the trusses together at the centers of the latter.

8. The hull according to claim 7, having cross

beams to connect the centers of the K-frames of the trusses to the additional bulkheads.

9. In a hull for a dry dock pontoon, the combination of parallel top and bottom beams arranged in pairs, bottom plates attached to the lower edges of said bottom beams, the upper edges of said plates having out-turned flanges, stiffening ribs passing through said beams, transverse battens secured to said flanges, uprights secured to the top and bottom beams, and braces secured to the uprights and the opposed faces of said pairs of beams.

10. A hull for a dry dock pontoon, having inside trusses extending side by side, from the middle towards the ends of said hull, bulkheads spaced from the ends of the pontoon and intersected by said trusses, some of said trusses being shorter and some longer than the remainder, the longer projecting beyond said bulkheads, the shorter trusses terminating at said bulkheads and short of said ends.

11. A hull for a dry dock pontoon, having trusses within the hull, said trusses extending side by side from the middle towards the ends, bulkheads spaced from the ends of the pontoon and intersected by said trusses, some of said trusses being shorter and some longer than the remainder, the longer projecting past said bulkheads, the shorter ones terminating at said bulkheads and short of said ends, and the longer trusses having relatively heavy portions at said ends to resist upward bending moments.

FREDERIC R. HARRIS.
